UNITED STATES PATENT OFFICE.

WILLIAM H. SAUVAGE, OF FLUSHING, NEW YORK, ASSIGNOR, BY MESNE ASSIGNMENTS, TO GOULD COUPLER COMPANY, OF NEW YORK, N. Y.

SLACK ADJUSTER.

Application filed February 6, 1920. Serial No. 356,754.

To all whom it may concern:

Be it known that I, WILLIAM H. SAUVAGE, a citizen of the United States, residing at Flushing, Long Island, in the county of 5 Queens and State of New York, have invented certain new and useful Improvements in Slack Adjusters, of which the following is a specification.

This invention relates to improvements 10 in slack adjusters and more particularly to that type of slack adjusters adapted to be applied to the trucks of railway vehicles, although it is of course to be understood that without material modification certain 15 features thereof are applicable to other types of brake rigging.

One of the objects of the present invention is to provide a simple and practical slack adjuster which may be inexpensively 20 manufactured and assembled.

A further object is to provide an improved slack adjuster which will be reliable and efficient in use and operation and not easily affected by atmospheric conditions or 25 the dust and dirt of the road.

A further object is to provide a reliable and efficient slack adjuster particularly applicable to the brake rigging of car trucks.

Other objects will be in part obvious and 30 in part hereinafter pointed out.

In the accompanying drawings wherein one of various possible modifications of the present invention is shown,

Figure 1 shows in elevation such parts of 35 the brake rigging and truck as are necessary to understand the present invention, and,

Figure 2 is an end elevational view.

Referring now to the drawings in detail 40 5 the frame work of a car truck of standard construction provided with wheels 6, brake beams 7 and brake shoes 8 adapted to coact with the periphery of the wheels 6.

At one side of bolster 10 is a live lever 45 11 the upper end of which is connected by pull rod 12 to any convenient source of power. At the opposite side of the bolster 10 is a bracket 13 pivotally connected at 14 50 with the truck frame and provided with a series of openings 15 to one of which is pivotally connected the upper end of dead lever 16. Both the live and dead levers are pivotally mounted near their lower central parts in struts 17 carried by the brake 55

beams 7. To the lower end of the live lever 11 is pivotally connected at the point 18 a tubular member 20 with which is adapted to telescope a solid rod 21 pivotally connecting at 22 to the lower end of dead lever 16. The tubular member 20 carries a housing 23 in which are mounted a plurality of dogs 24 coacting with the rod 21 and normally held in biting engagement therewith by means of a coil spring 25 urging the dogs into canted relation whereby relative inward movement of the rod 21 is prevented during application of the brakes. This structure, however, permits a relative outward movement of the rod 21 on release 70 of the brakes when the parts are being restored to normal position by reason of the return spring 26 after excess travel has taken place, due to wear of the parts. Interposed between the live and dead levers 75 is an adjusting rod 27 one end of which 28 has a lost motion or slotted pivotal connection with the live lever 11. The opposite end passes through a housing 30 supported in any convenient manner from the strut 80 17 or brake beam within which is a dog 31 normally held in canted position by means of coil spring 32 surrounding the rod 27, whereby movement of this rod toward the right is prevented during application of the 85 brakes.

These dogs it will be understood are merely rectangular or other suitably shaped pieces of metal having openings with case hardened edges through which the rods are 90 adapted to pass, whereby a movement of the rods in one direction is positively prevented due to the biting engagement with the edges of the opening, which nevertheless will permit the rods to move relatively in 95 the opposite direction when necessary to take up the slack.

The operation of this device is substantially as follows:

On application of the brakes, the upper 100 end of the live lever moves relatively towards the left and travels freely to the limit of the slot 28. If, however, due to wear of the brake shoes, excess travel occurs exceeding that provided for by the slot 105 28, then the adjusting rod 27 is moved relatively outwardly or towards the left with respect to the housing 30, the rod being free to slip through the dog 31 in that direction. At the same time, the lower end of live lever 110

11 moves towards the right and push rod 20 and 21, reacting with this movement, carries the lower end of the dead lever 16 towards the right. Thus the brake shoes 8 5 are brought into engagement with the periphery of the wheels 6.

On release of the brakes the return spring 26 tends to bring the live lever back to full release position against the bolster 10, as 10 shown in Figure 1. The brake shoes first drop back to clearance position, as permitted by reason of the slot 28 after which this point acts as a fulcrum, being held against further movement by the dog 31, and causes 15 a relative separation of the points 18 and 22, by causing an extension of the rods 20 and 21, an action that is made possible by the position and relation of the holding dogs 24 which permit movement of rod 21 20 relatively outward or toward the right with respect to housing 23, but prevent movement of the rod in the opposite direction. In this manner the push rod 21 is extended 25 an amount exactly corresponding to the excess travel of the brake rigging.

The parts are all of practical mechanical construction and there is little or no danger of any slipping of the telescopic parts or freezing or jamming of the parts into fixed 30 relation whereby a proper operation of the brakes is prevented.

It is thus seen that the invention provides a reliable and efficient slack adjuster mechanism particularly adapted for use on 35 railway vehicle trucks and accomplishes among others all of the objects and advantages herein set forth.

Considerable variation of the details as 40 described herein may be resorted to without departure from the spirit of the invention which is to be construed in the light of the following claims:

1. In a slack adjuster mechanism, in combination, live and dead levers, a source of 45 power connected with the live lever, a telescopic push rod connecting the live and dead levers, an adjusting rod connecting the live and dead levers, said telescopic rod comprising two parts capable of telescopic movement, a housing means connecting said parts in sliding relation, holding means within 50 said housing whereby said parts are held positively against movement to a shorter effective length, said adjusting rod slidably 55 mounted at both ends and provided with a housing and holding means at one end whereby the rod is positively held against movement in one direction.

2. In a slack adjuster mechanism, in combination, live and dead levers, a source of 60 power connected with the live lever, a telescopic push rod connecting the live and dead levers, an adjusting rod connecting the live and dead levers, positively connecting holding 65 means associated with both rods, said

means comprising housings, dogs in the housings and means normally holding the dogs in canted relation, whereby the rods are free to move to a greater effective length but are positively held against movement in 70 the opposite direction.

3. In a slack adjuster mechanism, in combination, live and dead levers, a two part telescopic push rod connecting the lower ends of 75 said levers, an adjusting rod connecting said levers and lying substantially parallel to the push rod, said rods each extending through a housing, dogs within the housings engaging the rods, and means holding said dogs in biting relation therewith whereby one 80 rod is free to move relatively in one direction and the other rod free to move relatively in the same effective direction only, and whereby, upon application of the brakes, one rod is held positively against a sliding 85 movement and, upon release of the brakes, the other rod is held positively against a sliding movement.

4. In a slack adjuster mechanism, in combination, live and dead levers at opposite 90 sides thereof carrying brake shoes adapted to coact with the wheels, a two part telescopic push rod connecting the lower ends of the live and dead levers, positive take up and holding means connecting said parts 95 and holding them against relative sliding movement in one direction only, an adjusting rod connecting the live and dead levers slidably engaged at both ends, the engaging means at one end, including a housing with a holding dog therein associated with urging means whereby the adjusting rod is free to slide to a greater effective length only, upon application of the brakes, and is positively held against sliding movement at that 100 end upon release of the brakes.

5. In a slack adjuster mechanism, in combination, live and dead levers at opposite sides thereof carrying brake shoes adapted 110 to coact with the wheels, a two part telescopic push rod connecting the lower ends of the live and dead levers, positive take up and holding means connecting said parts permitting free movement in one direction only, upon release of the brakes an adjusting rod connecting the live and dead levers, being loosely connected to one lever and slidably connected to the other lever by a housing with a holding dog therein adapted to permit free movement of the adjusting rod 115 in the one direction only, and means for restoring said parts to normal position after application of the brakes to take up the slack.

6. In a slack adjuster mechanism, in combination, a truck frame, live and dead levers at opposite sides thereof having brake 125 shoes adapted to coact with the wheels, a two part telescopic push rod having positively connecting dogs co-acting with the ef- 130

fective ends of said two parts whereby relative free movement is permitted in one direction and prevented in the opposite direction, an adjusting rod having a lost motion, 5 pivotal connection with one lever and a housing carried by the other lever supporting the opposite end of said adjusting rod, a dog within said housing urged into biting engagement with the rod and adapted to 10 permit a free movement thereof in a like effective direction to the free movement of the push rod, and to prevent movement in the other direction.

7. In a slack adjuster mechanism, in combination, a truck frame, live and dead levers at the opposite sides thereof, brake beams and shoes pivotally connected with the levers near their central parts, a two part telescopic push rod connecting the lower ends 15 of said levers, positive holding means connecting the effective ends of said two parts, an adjusting rod having a lost motion pivotal connection with one lever, a housing carried by the other lever in which said 20 adjusting rod is adapted to slide, a holding dog in said housing and means urging said

dog in to biting relation with said rod whereby it is free to move in one direction and held against movement in the opposite direction.

30

8. In a slack adjuster mechanism, in combination, live and dead levers, a source of power connected with the live lever, an adjusting rod between said levers capable of sliding movement at both ends upon application of the brakes and of locking action at one end upon release of the brakes, a telescopic rod of two parts, means positively holding said parts in fixed relation upon application of the brakes and permitting a 35 sliding movement of the parts upon release of the brakes, a housing on each of said rods and locking dogs therein adapted to lock and release said rods in relatively alternate 40 relation.

45

In testimony whereof I affix my signature in the presence of two witnesses.

WILLIAM H. SAUVAGE.
